CLAIM

The ornamental design for a solar landscape spotlight, as shown and described.

DESCRIPTION

FIG. 1 is a front elevational view of a solar landscape spotlight showing a first embodiment of my new design; FIG. 2 is a rear elevational view of the solar landscape spotlight of FIG. 1;

FIG. 3 is a left side elevational view of the solar landscape spotlight of FIG. 1;

FIG. 4 is a right side elevational view of the solar landscape spotlight of FIG. 1;

FIG. 5 is a top plan view of the solar landscape spotlight of FIG. 1;

FIG. 6 is a bottom plan view of the solar landscape spotlight of FIG. 1; and,

FIG. 7 is a perspective view of the solar landscape spotlight of FIG. 1;

FIG. 8 is a front elevational view of a solar landscape spotlight showing a second embodiment of my new design; FIG. 9 is a rear elevational view of the solar landscape spotlight of FIG. 8;

FIG. 10 is a left side elevational view of the solar landscape spotlight of FIG. 8;

FIG. 11 is a right side elevational view of the solar landscape spotlight of FIG. 8;

FIG. 12 is a top plan view of the solar landscape spotlight of FIG. 8;

FIG. 13 is a bottom plan view of the solar landscape spotlight of FIG. 8; and,

FIG. 14 is a perspective view of the solar landscape spotlight of FIG. 8.

The broken lines illustrate portions of the spotlight that form no part of the claimed design.

1 Claim, 14 Drawing Sheets
